ANTIGLARE DEVICE FOR HEADLIGHTS

Jacob E. Fisher, Detroit, Mich., assignor of one-half to George R. Feuerlein, Detroit, Mich.

Application March 28, 1932. Serial No. 601,555

4 Claims. (Cl. 240—48.6)

This invention relates to improvements in anti-glare devices for headlights. The curvature of the reflectors now employed in many headlights is such that light beams are thrown substantially horizontally therefrom, and in consequence it is the light reflected by the upper portions of the reflectors which dazzles drivers of approaching vehicles.

It is an object of this invention to provide an anti-glare device wherein a tinted translucent element is so arranged that when the device is mounted in a headlight the light which strikes the upper portion of the reflector must first pass through the said element. Thus I aim to provide a means for eliminating the dazzling effect of light beams thrown substantially horizontally by the upper portion of a reflector without reducing the brilliance of the light thrown by its lower portion.

Another object of the invention is to provide an anti-glare device the frame of which is adapted to be resiliently mounted on a socket of a light bulb, and wherein the translucent element is resiliently held both by the frame and also by a retaining member which is in engagement with the frame and also bears against the outer end of the light bulb.

A further object of the invention is to provide an anti-glare device which is readily attachable to or detachable from a light bulb, and which, when in position thereon, is so supported that it will not move or rattle.

With these and other objects and advantages in view which will become apparent as the specification proceeds, the invention is hereinafter more fully described with the aid of the accompanying drawing, in which:

Figure 1 illustrates a reduced cross sectional view of a headlight showing the invention in position on the light bulb mounted therein.

Figure 2 is a front view of the device, and

Figure 3 is an inverted plan thereof mounted on a light bulb.

Figure 4 is a section on the line 4—4 of Figure 2.

Figure 5 shows a section on the line 5—5 of Figure 3.

Figure 6 is a perspective view of the translucent element.

Figure 7 is a perspective view of the frame, and

Figure 8 is a perspective view of the retaining member.

Referring to the drawing, 1 designates an ordinary headlight having a reflector 2 therein

through which the socket 3 of a light bulb 4 projects.

My anti-glare device consists primarily of a frame 5, a translucent element 6, and a retaining member 7.

The frame 5 which is preferably a stamping consists of a transverse portion 8 which is upwardly flexed intermediately of its width and has a downturned rear margin 8a. Held as by a downwardly and rearwardly flexed lug 8b integral with the transverse frame portion 8 and bearing against the underside of the latter adjacent its margin 8a is the intermediate portion 9a of a downwardly extending spring 9 which is substantially in the form of an inverted U. The extremities 9b of the spring are inturned towards one another. Extending forwardly from opposite sides of the transverse portion 8 are outwardly bowed arms 10. The latter are of angle section so as to form horizontal supporting ribs 10a and vertical flanges 10b which project upwardly from the outer sides of the said ribs. Moreover these arms 10 are somewhat resilient so that they may be moved outwardly relative to one another and will spring back to their normal spacing shown. The outer extremities of the ribs 10a are downwardly turned as shown at 10c.

The translucent element 6, which is of substantially uniform thickness throughout, is transversely upwardly curved from its opposite margins which rest upon the supporting ribs 10a while inward spring pressure exerted against opposite sides of the element 6 by the vertical flanges 10b holds the said element against transverse movement on the ribs 10a. The rear extremity of the element 6 is also longitudinally downwardly curved and extends beneath a forwardly projecting flange 6a integral with the transverse portion 8 of the frame 5. Towards the front margin of the element 6 and substantially centrally of its width a recess 6b is formed in its upper face.

The retaining member 7 is annular and has opposed horizontal projections 12 and a vertical projection 13 all of which extend substantially radially from the said member. The horizontal projections 12 have upwardly extending lugs 12a at their extremities and the vertical projection 13 has a rearwardly and downwardly folded lug 13a, at its extremity. All the projections 12 and 13 are creased transversely usually adjacent the member 7 in order to impart a measure of resilience to their outer extremities. The horizontal projections 12 are so positioned as to ex-

tend beneath the arms 10 and the downturned extremities 10c of the latter rest adjacent the front faces of the said projections while the upwardly extending lugs 12a rest against the front 5 margins of the element 6. The rearwardly and downwardly folded lug 13a engages the recess 6b formed in the element 6 and holds the bottom edges of the latter on the arms 10.

When the device is in position on the bulb 4 10 the inturned spring extremities engage opposite portions of the socket periphery below the center of the latter while the upper peripheral portion of the socket is contacted by the downturned rear margin 8a of the frame 5 substantially centrally of its width. The outer extremity of the light bulb 4 projects into and is engaged by the 15 annular retaining member 7.

While in the foregoing the preferred embodiment of the invention has been described and 20 shown, it is understood that the construction is susceptible to such alterations and modifications as fall within the scope of the appended claims.

What I claim as my invention and desire to secure by Letters Patent is:

25. 1. A device of the character described comprising a frame, means thereon for engaging the socket of a light bulb, arms on said frame extending along opposite sides of the light bulb, a translucent element supported by said arms 30 and extending partly around the bulb, and a retaining member in engagement with said arms against which the front extremity of the light bulb seats said member having a resilient lug thereon which engages the outer face of said 35 element adjacent its front extremity and holds the lateral margins of said element on said arms.

2. A device of the character described comprising a transverse frame portion having a substantially U-shaped spring dependently mounted 40 thereon, the extremities of said spring being in-turned and adapted to engage opposite sides of the periphery of a light bulb socket beneath its horizontal axis, a portion of the transverse frame resting upon the upper portion of the socket periphery, outwardly bowed arms extending from the transverse frame portion, a translucent element supported on said arms and extending 45 partly around the light bulb for substantially the entire length of the latter, and a retaining member in engagement with the front extremity of said arms which holds the lateral margins of 50 said element in contact with said arms.

frame resting on the upper portion of the socket periphery, outwardly bowed arms extending from the transverse frame portion, a translucent element supported on said arms extending partway around the light bulb for substantially the entire length of the latter, a flange on the transverse frame portion between which and said arms the rear extremity of the element lies, said flange holding that extremity of the element on said arms, and a retaining member in engagement 80 with said arms, the front extremity of the element, and the outer end of the light bulb.

3. In a device of the character described, the combination of a frame having means thereon to hold it on a light bulb, arms on said frame, a translucent element supported by said arms and extending partway around said light bulb for substantially its entire length, an annular retaining member into which the outer extremity of the light bulb fits, projections on said member in engagement with the outer extremities of the arms, and another projection on said member having a lug at its outer extremity which resiliently engages the element intermediately of 90 its width adjacent its front margin.

4. A device of the character described comprising a transverse frame portion having a substantially U-shaped spring dependently mounted thereon, the extremities of said spring being in-turned and adapted to engage opposite sides of the periphery of a light bulb socket beneath its horizontal axis, a portion of the transverse frame resting upon the upper portion of the socket periphery, outwardly bowed arms extending from the transverse frame portion, a translucent element supported on said arms and extending partway around the light bulb for substantially the entire length of the latter, and a retaining member in engagement with the front extremity of 105 said arms which holds the lateral margins of 110 said element in contact with said arms.
